**LOCKING CLOSURE DEVICE FOR VIALS
AND THE LIKE**
Lorne A. Caldwell, 328 W. 2nd St., Cornwall,
Ontario, Canada
Filed Mar. 26, 1965, Ser. No. 442,944
9 Claims. (Cl. 215—9)

This invention relates to a locking closure device for vials, bottles and the like.

This invention is particularly related to a locking closure device adapted for use on vials, bottles and other containers which are used to contain potentially poisonous substances. Where such substances are used in the home, it is very desirable to have the substances in a container which is very difficult or impossible for young children to open.

Attempts have been made in the past to provide for bottles and vials caps or covers which are fastened to the bottle or vial in such a manner that young children could not remove the cap or cover but adults could readily remove the cap or cover. For example, it is known to use a screw top closure which closes very tightly and requires some force to loosen or open. For another example, it is known to have a resilient snap-on cap of plastic material which may be pressed over a retaining ridge on the rim of a bottle or vial and which requires a good force applied to the edge of the cap to remove the cap.

None of the prior art safety closure devices have been entirely satisfactory. Some of the closure caps have been difficult for adults to remove because of the force required. Various of the prior art closure caps are capable of being removed by young children who have, on occasion, made diligent use of teeth, fingers and other available objects to intentionally or inadvertently remove a closure cap from a vial or bottle.

It is therefore an object of this invention to provide for vials and the like a locking closure device which is difficult or impossible for young children to remove.

It is another object of this invention to provide for use on vials and the like a safety closure device of an uncomplicated design having few parts which may be easily opened or closed by adults.

These and other objects and advantages will be apparent from the following description taken in conjunction with the accompanying drawings in which:

FIGURE 1 is an isometric view of a bottle and a closure cap in accordance with the invention.

FIGURE 2 is an exploded view, partly in section, showing the bottle and the component parts of the closure cap of the invention.

FIGURES 3, 4 and 5 are views taken respectively along lines 3—3, 4—4, and 5—5 of FIGURE 2.

FIGURE 6 is a sectional view of a portion of the bottle and the closure cap in its unlocked position.

FIGURE 7 is a sectional view of a portion of the bottle and the closure cap in its locked position, and

FIGURE 8 is a side view of a portion of the closure device in an alternative embodiment of this invention.

Briefly, the invention is for a locking closure device for vials and the like having an opening defined by a rim and being provided with a plurality of bayonet lugs. The device comprises a cap for the vial having a top and a depending skirt with a mating bayonet slot for each bayonet lug. The walls defining each said slot form at the terminating end thereof a retaining portion. A stem member passes through an aperture in the top of the cap making sliding engagement with the walls of said aperture. A head is on one end of said stem member and a base on the opposite end. The base is positioned in

2

the region of the cap defined by the skirt. One side of the base is adapted to engage the rim of the vial and the other side is provided with a plurality of ramps. The interiorly facing surface of the top is provided with a mating recess for each ramp on the base, and each such recess is separated from the adjacent recess by a flat part of the top. Thus the stem member, with head and base, may be positioned in a first position with the ramps on the base received in the respective recess in the top or may be positioned in a second locking closure position where the peaks of the ramps each engage an opposing flat part of the top.

In the first position, the cap may be moved so that the bayonet lugs traverse the respective bayonet slot, while in the second position the base engages the rim of the vial so that, when the cap is on, the bayonet lugs are in the retaining portion of the respective bayonet slot and the base bears against the rim to prevent the bayonet lugs from being moved from the retaining portion and thus keep the cap in that position.

Referring now to the drawings, and particularly to FIGURES 1 and 2, a vial or bottle 10 is shown having a rim 11, and also having bayonet lugs 12 spaced at equal distances around the rim 11. Three lugs 12 are shown in the depicted embodiment. A cap 14 is the closure for the vial. The cap 14 has a top 16 and a depending skirt 15. The top 16 is provided with a central aperture 17 and a recess 18 in the outer surface thereof. The aperture 17 has walls which define a circular portion 20 and a fan-shaped keyway portion 21 which extends over a little less than one third of the circumference of the circular portion. The aperture 17 is clearly shown in FIGURES 4 and 5.

The skirt 15 of cap 14 has three bayonet slots 22 for receiving the bayonet lugs 12 in a well known manner. Each bayonet slot 22 is approximately in the shape of an inverted "J" and has a longitudinally extending portion 23 with an open lug-receiving end, a lateral portion 24 and a retaining portion 25 at the end of the lateral portion 24 substantially as shown, for example in FIGURE 6. When the cap is being placed on the bottle, the slots 22 are fitted over lugs 12 so that the lugs 12 first traverse the longitudinal portion 23, then the lateral portion 24 and are positioned in the retaining portion 25.

The cap 14 has, passing through aperture 17, a stem member 26 having a longitudinal key 27 extending along one side. This is best seen in FIGURE 2. The key 27 is received by the keyway portion 21 of aperture 17. The stem member 26 makes a sliding engagement with the walls of aperture 17 which permits longitudinal movement of the stem member 26 within the aperture and rotational movement as limited by the travel of key 27 in keyway portion 21.

A head 28 is provided on the end of stem member 26 which extends exteriorly of cap 14. The head 28 may be integral with stem member 26 or it may be secured to stem member 26 by cement or any other suitable means. The head 28 is provided with a slot 30 diametrically across its upper surface. The slot 30 is conveniently wide enough to receive the edge of a penny, and preferably is wide enough to receive the edge of a penny allowing some free play. The slot 30 also preferably has a curved concave base which meets the top surface of the head substantially at the outer edge of the head. The slot configuration will be referred to herein-after.

On the opposite end of stem member 26 is a base 31. This is best shown in FIGURES 2 and 3. As shown, base 31 has a recess for receiving stem member 26 whereby they may be secured together with cement or other adhesive. However base 31 and stem member 26 may

be secured together by any suitable means or, depending on the manner of securing head 28, it is possible to form base 31 and stem member 26 integrally with one another. The base 31 has a rim engaging side to which may be secured a gasket 32 (indicated in phantom) for effecting a good seal with the rim of vial 10. Base 31 has a ramp side opposite the rim-engaging side, and this has three ramps 33. The ramp side of base 31 is shown in FIGURE 3. Each ramp 33 has a generally saw-tooth shaped profile. That is each ramp 33 has an inclined surface 34 and a flat peak 35. The trough or base of the profile also has a flat portion. The underside of top 16 has three recesses 36 of a shape and position to receive the three ramps 33. The recesses 36 thus have troughs with a flat portion and a flat portion at the surface of the base. These flat portions on the base surface which separate the recesses are designated as intermediate flat parts 37. The recesses 36 in top 16 are indicated in dotted lines in FIGURE 2 and are shown in FIGURES 5, 6 and 7, for example.

The operation of the closure device will now be described with reference to FIGURES 6 and 7. Considering first the procedure followed when placing the closure cap on the bottle, the head 28 is rotated to the right until key 27 engages one limit of keyway portion 21 of aperture 17. The head 28 may conveniently be rotated by inserting the edge of a coin in slot 30. As the head 28, stem member 26 and base 31 are secured together and move as a unit, the base 31 is positioned at a corresponding limit of rotational travel. The keyway portion 21, the ramps 33 and the recesses 36 in the top are so positioned with respect to one another that, when the head is rotated to the right as described, the ramps 33 are in a position to be received in recesses 36 as indicated in FIGURE 6. Because ramps 33 are in a position to be received in mating recesses 36, the unit comprising base 31, stem member 26 and head 28 may be moved longitudinally outward as in FIGURE 6. Now the cap 14 is placed over the neck or rim of vial 10 with the bayonet lugs 12 entering the open end of portions 23 of bayonet slots 22. As the cap 14 is moved longitudinally towards the vial 10 the bayonet lugs 12 traverse the longitudinal portions 23 of bayonet slots 12 to a position substantially as indicated in FIGURE 6 with the rim of vial 10 pressing base 10 outwardly so ramps 33 are received in respective recesses 36. The cap 14 may now be turned to the right and bayonet lugs 12 traverse the lateral portions 24 of slots 22. Once in this position the cap 14 may be moved longitudinally outwards or away from vial 10 to position bayonet lugs 12 in retaining portions 25 of bayonet slots 22.

In order to lock the closure device, head 28 is rotated to the left to its other limit of travel. Again this may conveniently be done using the edge of a coin in slot 30. As head 28 is rotated, and of course stem member 26 and base 32 rotate with it, the inclined surfaces 34 of ramps 33 bear against the corresponding inclined surfaces of recesses 36 moving the base 31 towards the rim of vial 10. The rim-engaging side of base 31 bears against the rim of vial 10, and if a gasket 32 is provided it is pressed against the rim of vial 10 to form a seal. As the head 28 reaches its limit of travel to the left, the ramps 33 move so that their flat peaks 35 bear against the flat intermediate parts 37 of top 16 substantially as shown in FIGURE 7. Thus the base 31 presses on one side against the rim of vial 10 and on the other side, via the peaks 35, on the top 16. This presses the rim and the top in directions longitudinally away from one another. The cap 14 therefore cannot be moved towards the vial and bayonet lugs 12 are held in retaining portions 25 of bayonet slots 22.

It will be seen that the reverse procedure may be used to unlock and remove cap 14. Briefly, head 28 is rotated to the right, cap 14 is pressed towards vial 10, cap 14 is rotated to the left and may then be removed.

It was previously mentioned that key 27 and the keyway portion 21 of aperture 17 were arranged to limit the rotational movement of stem member 26 with head 28 and base 31 to less than 120 degrees, that is to the locked position in one direction and to the unlocked position in the opposite direction of rotation. This is to remove any ambiguity in the locked and unlocked positions which might occur, for example, if the top closure could be locked in two positions.

In the manufacture of a locking closure device as described herein, it is preferable that the movement of the stem with head and base, particularly in the locked position, should be stiff rather than loose. Thus, the rim-engaging side of base 31 (or gasket 32) should bear firmly against the vial rim when the device is in its locked position. This reduces the possibility of a chance opening of the vial which might occur if the fit were loose.

It will be apparent that the number of bayonet lugs and corresponding bayonet slots is not critical, however, at least two are required. Similarly the number of ramps and corresponding recesses is not critical. It is, however, desirable to have at least two.

If the safety feature is not of prime importance, the device may be made with a head 28 that projects farther from the cap 14 in order that it may be rotated by fingers to the locked or unlocked position. Alternately the "key" may be incorporated as an integral part of the head. However, when a slotted head 28 is used, an important safety feature is provided because a "key" such as a coin is required to lock and unlock the closure cap. It should be noted that the preferred construction is to have the head 28 flush with cap 14 or projecting only slightly. This prevents the gripping of the head 28 with fingers to unlock the closure cap.

It should be noted that slot 30 may be made just wide enough to receive the edge of a coin so that a coin can be used as a "key." However, if the slot 30 is made a little wider than the edge of a coin, a coin may still be used as a "key" and it makes it very difficult, if not impossible, to use a fingernail as the "key." This is particularly so with small fingernails of children.

The use of a concave base to the slot 30, if the slot extends only to the edges of the head or terminates short of the edges, will permit the use of a coin or other article with a curved edge as a "key." However this configuration will not accept a straight edge as a "key" as the edge will not go into the slot 30. This slot configuration may thus be used to reduce the number of "keys" that may be used to unlock the closure gap, and consequently may provide an additional safety factor.

An alternative embodiment of the invention is indicated in FIGURE 8. In this embodiment the gasket 32 is mounted to the base 31 by a spring 40. The spring may comprise one or more turns of a relatively flat helical spring. This embodiment may be desirable in some instances where the vial is intended to contain a liquid to ensure an even seal around the rim of the vial. It will, of course, be apparent that the spring should not affect the locking of the closure cap. That is, when the closure cap is locked, the cap 14 should not be able to be moved towards the vial (compressing spring 40) sufficiently to permit the bayonet lugs to pass through the lateral portions of the bayonet slots to release the cap. Consequently the distance between gasket 32 and base 31 when the closure cap is locked should be small compared to the distance the bayonet lugs are from the lateral portion of the bayonet slots.

It is believed that the locking closure device according to the invention set forth herein provides a suitable closure for vials, bottles and the like which are used to contain potentially poisonous substances. The locking closure device is difficult or impossible for young children to operate, and it is easily operated by adults.

I claim:

1. A locking closure device for vials and the like having an opening defined by a rim and being provided with a plurality of bayonet lugs, comprising

a cap having a top and a depending skirt provided with a mating bayonet slot for each said bayonet lug, the walls defining each said slot forming at the terminating end thereof a retaining portion, said top of said cap having a central aperture, a stem member passing through said aperture in sliding engagement with the walls defining said aperture, a head on one end of said stem member exteriorly of said cap, a base on the opposite end of said stem member positioned within the region of said cap defined by said skirt,

said base having a rim-engaging side and a ramp side provided with a plurality of ramps, the interiorly facing surface of said top being provided with a mating recess for each ramp on said base, each said recess being separated from the adjacent recess by an intermediate flat part,

the said stem member with head and base having a first retracted position where the said ramps are received in the respective recesses in said top and a second closure locking position where the said ramps at the peaks thereof engage the intermediate flat parts of said top.

2. A locking closure device for vials and the like having an opening defined by a rim and being provided with a plurality of bayonet lugs, comprising

a cap having a top and a depending skirt with a mating bayonet slot for each said bayonet lug,

each said slot having walls defining a longitudinally extending portion with an open lug-receiving end and an inner end, a lateral portion extending transversely from said inner end, and a closed retaining portion at the end of said lateral portion remote from said inner end,

said closed retaining portion extending a predetermined distance parallel to and spaced laterally from said longitudinal portion,

said top of said cap having a central aperture,

a stem member passing through said aperture and making longitudinal and rotational sliding engagement with the walls defining said aperture,

said stem member having a first end on the side of said top exteriorly of said cap and a second end on the opposite side of said top within the region defined by said skirt,

a head on said first end,

a base on said second end having a first rim-engaging side and a second side provided with a plurality of ramps,

the interiorly facing surface of said top of said cap being provided with a mating recess for each ramp on said second side of said base, said mating recesses being separated by intermediate flat parts of said top,

the said stem member, head and base having a first position where said ramps on said second side of said base are received in the recesses of said top permitting the cap to be moved inwardly towards a vial and rotated with said

bayonet lugs traversing said lateral portions, and a second position where the said ramps on said second side of said base engage said intermediate flat parts of said top holding the base a predetermined distance from said top for engaging with said first side thereof a vial rim to retain each said bayonet lug in a respective one of said retaining portions of said bayonet slots.

3. A locking closure device as defined in claim 2 and further including means on said cap limiting the rota-

tional movement of said stem member with head and base to said first position in one direction of rotational movement and to said second position in the opposite direction of rotational movement.

4. A locking closure device as defined in claim 2 in which the aperture defining walls of said top are formed to define a circular portion and a fan-shaped keyway portion, and in which said stem member further includes a longitudinal key passing through said fan-shaped keyway portion,

said key engaging the ends of said fan-shaped portion to limit the rotational movement of the stem member within said aperture and the head and base to said first position in one direction of rotational movement and to said second position in the opposite direction of rotational movement.

5. A locking closure device for vials and the like having an opening defined by a vial rim and being provided with a plurality of bayonet lugs spaced around said rim, comprising

a cap having a top and a depending skirt with a mating bayonet slot for each said bayonet lug,

each said bayonet slot having walls defining a longitudinally extending portion with an open lug-receiving end and an inner end, a lateral portion extending transversely from said inner end, and a closed retaining portion at the end of said lateral portion remote from said inner end,

said closed retaining portion extending a predetermined distance substantially parallel to and spaced laterally from said longitudinal portion,

said top of said cap having a central recess in the outwardly facing side thereof and a substantially central aperture,

a stem member passing through said aperture and making longitudinal and rotational sliding engagement with the walls defining said aperture,

said stem member having a first end extending towards said outwardly facing side of said top and a second end extending towards the opposite side of said top into the region defined by said top and said skirt,

a head on said first end having a size to fit within said recess in said top of said cap with the outer surface of said head substantially flush with the adjacent portion of said top,

a base on said second end having a first rim-engaging side and a second opposite side facing said top and provided with a plurality of spaced ramps,

the interiorly facing surface of said top of said cap being provided with a mating recess for each said ramp on the second side of said base, said mating recesses being separated by intermediate flat parts of said top,

the said stem member, with head and base, having a first position where said ramps on said second side of said base are positioned to be received in the mating recesses in said top permitting the cap to be moved inwardly towards said vial and rotated with said bayonet lugs traversing said lateral portions, and a second position where said ramps engage said intermediate flat parts of said top holding the base a predetermined distance from said top for causing engagement between said first side of said base and the rim of the vial to retain each bayonet lug in a respective one of said retaining portions of said bayonet slots.

6. A closure device as defined in claim 5 in which the outward surface of said head is provided with a diametrically extending slot having a curved concave base, said base meeting said outward surface substantially at the edges thereof.

7. A closure device as defined in claim 5 in which the ramps have an inclined surface and a flat peak, said peak of each said ramp engaging an opposing intermediate flat part of said top in said second position of said stem member with head and base.
8. A closure device as defined in claim 5 and further including a gasket of resilient material secured to said first side of said base for sealing engagement with said rim of said vial.
9. In combination with a vial having a neck portion terminating in a rim defining a vial opening and having a plurality of outwardly projecting bayonet lugs evenly spaced around said neck portion adjacent said rim, a closure cap comprising
- 10 a cap top and a depending skirt provided with mating bayonet slots for said bayonet lugs,
- 15 the walls defining each said bayonet slot forming at the terminating end of said slot a lug retaining portion,
- 20 said top having a central cylindrical recess in the outwardly facing side thereof and a substantially central aperture therethrough of smaller cross-section than said recess,
- 25 a stem member passing through said aperture and making sliding engagement with the walls defining said aperture,
- 30 a head on said stem member on the end thereof projecting to the outwardly facing side of said top having a substantially cylindrical form of a size for fitting within said cylindrical recess,
- 35 a base on the end of said stem member opposite to said head having a first side facing said top and a second side opposite said first side,
- 40 three ramps formed on the said first side of said base, evenly spaced around the outer portion thereof, each said ramp having a generally saw-tooth shaped profile with a flat portion in the trough and a flat portion at the peak,
- 45 the interiorly facing surface of said top of said

- 5 cap being provided with a mating recess for each said ramp having a flat portion in the trough and a flat portion at the base surface intermediate the mating recesses,
- 5 a resilient sealing gasket mounted to said second side of said base,
- 10 spring means secured to said base urging said gasket away from said base,
- 15 retaining means limiting the travel of said gasket to a predetermined distance from said base,
- 20 said stem member with said head and base having a first position where said ramps are opposite said mating recesses in said top for reception therein permitting the cap to be moved inwardly towards the vial and rotated with the bayonet lugs traversing the bayonet slots, and a second position where the flat portions at the peaks of said ramps engage the flat portions at the base surface intermediate said recesses holding the base a predetermined distance from said top and pressing said gasket firmly against said rim of said vial to retain said bayonet lugs in the lug-retaining portions of said bayonet slots, and
- 25 means limiting the rotational movement of said stem member with head and base to said first position in one direction of rotational movement and to said second position in the opposite direction of rotational movement.
